US0D1069835S

(12) **United States Design Patent** (10) **Patent No.:** **US D1,069,835 S**
(45) **Date of Patent:** **** Apr. 8, 2025**

(54) **DISPLAY SCREEN OR PORTION THEREOF
WITH GRAPHICAL USER INTERFACE**

(71) Applicant: **Sonos, Inc.**, Santa Barbara, CA (US)

(72) Inventors: **Brandon Lynne**, Santa Barbara, CA (US); **Ryan Kitson**, Santa Barbara, CA (US)

(73) Assignee: **SONOS, INC.**, Goleta, CA (US)

(**) Term: **15 Years**

(21) Appl. No.: **29/912,777**

(22) Filed: **Sep. 22, 2023**

Related U.S. Application Data

(63) Continuation of application No. 29/785,652, filed on May 26, 2021, now Pat. No. Des. 1,003,910, which is

(57) **CLAIM**

The ornamental design for a display screen or portion thereof with graphical user interface as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with graphical user interface according to a first embodiment of the invention; and,

FIG. 2 is a front view of a display screen or portion thereof with graphical user interface according to a second embodiment of the invention.

The dash dot dash broken lines are included for the purpose of showing the boundary of the claim and forms no part of the claimed design. The other broken lines are included for the purpose of showing portions of the article which form no part of the claimed design.

**1 Claim, 2 Drawing Sheets
(1 of 2 Drawing Sheet(s) Filed in Color)**

Related U.S. Application Data

a continuation of application No. 29/704,424, filed on Sep. 4, 2019, now Pat. No. Des. 922,419.
